CLAIM

The ornamental design for an electronic device, as shown and described.

DESCRIPTION

FIG. 1 is a top, front, right-side perspective view of a first embodiment of an electronic device;

FIG. 2 is a bottom, front, left-side perspective view thereof;

FIG. 3 is a top, back, right-side perspective view thereof;

FIG. 4 is a front view thereof;

FIG. 5 is a back view thereof;

FIG. 6 is a left-side view thereof;

FIG. 7 is a right-side view thereof;

FIG. 8 is a top view thereof;

FIG. 9 is a bottom view thereof;

FIG. 10 is a top, front, right-side perspective view of a second embodiment of an electronic device, showing a crosshatched pattern of the embodiment which represents a fabric (e.g., a woven fabric), and is understood to be distributed uniformly over the surface of the claimed design upon which the pattern occurs;

FIG. 11 is a bottom, front, left-side perspective view thereof;

FIG. 12 is a top, back, right-side perspective view thereof. The long dashed broken lines depict a seam on the back surface of the embodiment of the electronic design that forms no part of the claimed design;

FIG. 13 is a front view thereof;

FIG. 14 is a back view thereof;

FIG. 15 is a left-side view thereof;

FIG. 16 is a right-side view thereof;

FIG. 17 is a top view thereof; and,

FIG. 18 is a bottom view thereof.

The short dashed broken lines depict portions of the electronic device that form no part of the claimed design. The dot-dashed broken lines represent boundaries of the claimed electronic device and form no part of the claimed design.
